VACUUM SYSTEM CARRIER

Bruce J. Diem, P.O. Box 30071, Cincinnati, Ohio 45230

Filed Aug. 9, 1971, Ser. No. 170,398

Term of patent 14 years

Int. Cl. D9—07

U.S. Cl. D55—1 C

FIG. 1 is a perspective view of a vacuum system carrier showing my new design;

FIG. 2 is a top plan view;

FIG. 3 is a side elevational view;

FIG. 4 is a bottom plan view;

FIG. 5 is an end view;

FIG. 6 is a perspective view of a second embodiment of a vacuum system carrier showing my new design.

FIG. 7 is a top plan view;

FIG. 8 is a side elevational view;

FIG. 9 is a bottom plan view; and

FIG. 10 is an end view.

I claim:

The ornamental design for a vacuum system carrier, as shown and described.
